UNITED STATES PATENT OFFICE.

LUCIUS FREEMAN LITTLE, OF OWENSBORO, KENTUCKY.

APPARATUS FOR MAKING FLOUR AND MEAL.

1,399,437.

Specification of Letters Patent.

Patented Dec. 6, 1921.

Application filed May 14, 1920. Serial No. 381,348.

To all whom it may concern:

Be it known that I, LUCIUS FREEMAN LITTLE, a citizen of the United States, residing at Owensboro, in the county of

5 Daviess and State of Kentucky, have invented new and useful Improvements in Apparatus for Making Flour and Meal, of which the following is a specification.

The hereinafter described invention relates to apparatus for making flour and meal and is of that type of milling apparatus in which the break and reduction rolls by which the grain is reduced, and the centrifugal dressing devices, are placed in 10 close proximity to one another for short process milling, as distinguished from the long milling methods of some types of mills, the mill to which my improvements relate being exemplified, so far as its general 15 characteristics are concerned, by the Tattersall mill illustrated in Patent No. 1,037,805, dated September 3, 1912.

While the present mill of my invention is of this general type, it differs substantially therefrom, in that routing and handling of the stock is varied and shortened in a most desirable way, and the instrumentalities for bringing about this shortening and different routing are so combined as to 20 eliminate too frequent handling of the material under process of reduction, which is always desired so as to eliminate the breaking up of the bran and making bran attrition dust, which breaking up and making of 25 attrition dust occurs in some mills of this type now in use more or less as flour comes in contact with the outside coating of the bran, and is detrimental to the quality of the flour produced as this is the source of 30 low grade flour, and as the outside coating of the bran contains a coloring matter it is desirable to prevent flour and bran being sifted together or in any way come in contact with one another and this I do to 35 the minimum extent.

The breaking up of the bran particles and making bran attrition dust inevitably results from too frequent and continued handling of the stock after the grain has been 40 initially broken and the separation of the flour and middlings from the offal begins, the repeated passing of the stock through the centrifugals and conveyers breaking up the bran into microscopic particles and making 45 bran attrition dust, which cannot then be successfully dressed out, which remain

in the flour, and reduce, to that extent, its high quality, or as is practised in most mills, the separation of the flour into two or more grades.

I accomplish the result aimed at by so disposing the breaking rolls relative to each other, and to the dressing instrumentalities and the reduction rolls which act finally on the stock, as to reduce the handling of 60 the stock to minimum lengths of time and travel through the mill, reducing the interval of contact between flour and bran stock, without in any way affecting the thoroughness of reducing and separating, 65 and thereby improving the quality of the flour produced.

In order that the invention may be understood by those skilled in the art, I have shown in the accompanying drawings one 70 embodiment of my invention and in said drawings—

Figure 1 is a view in side elevation, parts of the structure being shown in section, of a mill embodying my invention,

Fig. 2 is a transverse vertical sectional view through the break roll section of the mill,

Fig. 3 is a transverse vertical section through the dressing or centrifugal section 85 of the mill,

Fig. 4 is a sectional view similar to Fig. 2, showing a different routing of stock from that disclosed in Fig. 2.

Referring to the drawings by numerals, 90 like numbers indicating like parts in the several views, 10 indicates the break roll section of the mill casing, and 11 indicates the dresser section of the mill casing, which mill casing may be of any suitable design 95 and construction. The break roll section 10 is provided at its top with any suitable hopper and grain feeding mechanism 12, into which the grain is poured and by which it is fed in a suitably regulated flow to the 100 milling instrumentalities.

Mounted within the mill section 10 in position to receive the grain flow from the hopper 12, are the first break rolls 13, which may be of any suitable construction and are 105 designed to receive and break the whole grain coming from the feeding instrumentalities. Below the break rolls 13 is mounted a vibrating scalping sieve, 14, provided with double screening elements 15 and 16, 110 the screen 15 being coarse so as to allow the passage of the fine middlings and the flour,

but preventing the larger grain particles from passing, which larger grain particles move down the inclined surface of the screen 15 and, by a suitable feed board 17, pass to a 5 second pair of break rolls 18. The second screen 16, which is inclined, receives the fine middlings and the flour, separates the flour and fine middlings by passing the flour through, and directs the middlings down its 10 inclined surface to a feed board 19 which delivers to the feed box 20 of the first pair of reduction rolls 21, it being understood that any suitable means for agitating the scalper sieve to promote the flow of the 15 stock thereon and its effective sieving is provided. The flour and fine middlings which pass the second screen 16 will be directed by a suitable feed board 22 to a conveyer 23 delivering to a centrifugal dresser 24 in the dresser section 11 of the mill where the flour will be dressed out in the manner customary in centrifugal dressers, the dressed out flour being delivered to any 20 suitable fall boards or slides which direct it 25 to a conveyer 25 at the bottom of the mill casing by which it is delivered ready for sacking.

The stock which passes from the first screen 15 of the scalping sieve is, as stated, 30 directed to the second pair of break rolls 18, and is further broken by said rolls, the stock coming from the said second pair of break rolls being delivered to a second scalping sieve 26 of a double screen construction 35 similar to the scalping sieve 14 already described. The coarse bran particles are retained on the coarse screen section 27 of the scalping sieve 26 and, flowing down its inclined surface to a suitable feed board 28, 40 are delivered to any suitable delivery point or if it is desired to separate the small amount of flour adhering to the bran particles, the bran may be tailed into a conveyer 31 by which it is delivered to a bran 45 receiving reel or duster 30 in the dressing section of the mill in which duster the flour is removed from the bran and falls to the conveyer 25 at the bottom of the dresser section, the bran being tailed out to any suitable 50 point of delivery. As an alternative a single-screen scalping sieve may be used at the second pair of break-rolls 18 and the throughs, consisting in part of flour and middling, be delivered to the conveyer 23 and thence to the centrifugal 24 where it 55 will be dressed, together with the throughs coming from the scalper of the first pair of breaking rolls, the tails of the coarse screen 27 going either to the bran scalper 60 reel 30 or by properly arranged fall boards, not shown, may be sent to 45, the conveyer carrying stock into the second reduction reel 46. The flour and small middlings from the feed board 22 pass through the 65 two screens 27 and 29 into conveyer 23 which

carries them into the centrifugal dresser 24 in the dressing section 11 of the mill. Preferably this centrifugal dresser 24 will be of large capacity, since, as will be observed, it receives the stock to be dressed from both 70 the first and second pairs of break rolls. The over tails of the fine screen 29 of scalper 26 flow down the trough 29^a to the hopper 20 of the first reduction rolls.

From the foregoing it will be seen that the 75 stock coming from the first and second pairs of break-rolls is subjected to but one dressing action in the centrifugal dresser 24, thus eliminating the difficulties heretofore experienced with mills in which all of the stock is 80 dressed after the action of the first pair of break-rolls, and again after the action of the second pair of break rolls. This eliminates objectionable attrition of the bran particles adhering to the middlings and the retention 85 of those particles and dust in the flour, and furthermore has the advantage of simplifying the construction, reducing initial cost of production and cost of maintenance, and shortening the routing of the stock through 90 the mill. The particles of stock too large for flour, or in other words, small middlings, in the centrifugal 24 are tailed out at the tail of reel 24 into a trough 24^a which may be slightly vibrated in order to make the middlings flow, said middlings running diagonally across rear of reel section and dropping into the end of the conveyer 24^a under the bran duster 31 which takes the middlings from reel 24 and from the bran duster reel 100 back to the hopper 20 of the first reduction rolls. The broad bran tails out to the offal bin from bran duster reel 30.

From the reduction rolls 21 the stock falls to a conveyer 36 by which it is delivered to 105 a centrifugal dresser 37 of usual construction where the flour is dressed through. The offal is tailed off to any suitable point of delivery, while the middlings which pass through the scalper section 38 are taken by a suitable conveyer 40 and delivered to an elevator 41 to chute 42 which delivers them to feed box 43 of a second pair of reduction rolls 44. The material which passes the second pair of reduction rolls is in finally reduced form and 110 falls to a conveyer 45 which carries it to a dresser 46 of the usual construction in the dressing section 11 of the mill, where the flour is dressed through, and the rest of the stock delivered from the final dresser 46 as 115 offal.

In the development shown in Fig. 4 the construction is identical with that shown in Fig. 2 heretofore described, except with respect to the routing of the stock from the 125 scalper for the second break-rolls. Instead of routing the stock as shown and described in connection with Fig. 1 to a bran duster, I dispense with that bran duster shown. In the construction shown in Fig. 4 the over- 130

tails from the screen scalper sieve 27 pass by a fall board 47 directly from the scalper screen 27 to a fall board 48 delivering directly to the conveyer 45 of the reel 46 for 5 the second reduction rolls 44. By this routing the stock passes directly to the reel 46 instead of going through the bran duster as in the form shown in Fig. 2.

The overtails of the fine scalper sieve 29 10 of the second break-rolls will, as before, pass to the hopper 20 of the first reduction rolls by means of a fall board 49 arranged as shown so as to pass the fall board 47 and deliver to the hopper 20.

15 With this arrangement the flour will be dressed out of the stock directly by the reel 46 without the interpositioning of the bran reel as shown in Fig. 2.

The driving mechanism for the break rolls, 20 reduction rolls, and centrifugal dressers may be of any suitable or desired construction. I do not describe or illustrate such driving mechanism in detail as it is well known and may be of various types, it being essential 25 only that it be of such character and so disposed as to give the necessary directions of rotation to the reducing and dressing instrumentalities described.

It is obvious that in physical embodiments 30 of my invention I may use any suitable or known types of rolls, roll adjusters, conveyers, and centrifugals, all of which are conventionally shown, and I do not, therefore, confine myself to any specific type.

35 I claim:

1. In a mill of the class described, the combination of a casing having a roll-section and a centrifugal-section, a plurality of pairs of break-rolls in said roll-section, 40 scalping sieves having coarse and fine screens for each pair of rolls, a centrifugal in said centrifugal-section, and means to receive and deliver the throughs from all of said scalping sieves to said centrifugal.

45 2. In a mill of the class described, the combination of a casing having a roll-section and a centrifugal section, a plurality of pairs of break-rolls in said roll-section, a scalping sieve having coarse and fine screens 50 for the first set of break-rolls to deliver the tailings to a succeeding set of break-rolls, a scalping sieve for the succeeding set of break-rolls, a centrifugal in said centrifugal-section, and means to receive and deliver the throughs from all of said scalping sieves to said centrifugal.

55 3. In a mill of the class described, the combination of a casing having a roll-section and a centrifugal-section, a plurality of 60 pairs of break-rolls in said roll-section, a scalping sieve having coarse and fine screens for the first set of break-rolls, a second set of break-rolls to which said coarse screen delivers its tailings, a scalping sieve for said 65 second set of break-rolls, a centrifugal in

said centrifugal section, a conveyer delivering to said centrifugal, and means for guiding the throughs from all of said sieves to said conveyer.

4. In a mill of the class described, the 70 combination of a casing having a roll-section and a centrifugal-section, a plurality of pairs of break-rolls in said roll-section, a scalping sieve having coarse and fine screens for the first set of break-rolls, a second set of break-rolls to which said coarse screen delivers its tailings, a scalping sieve for said second set of break-rolls, a centrifugal in said centrifugal section, a conveyer delivering to said centrifugal, means for 75 guiding the throughs from both sieves to said conveyer, a pair of reduction-rolls, and means for guiding the tailings from the fine screen of the scalping sieve for said first pair of break-rolls to said reduction-rolls. 80

5. In a mill of the class described, the combination of a casing having a roll-section and a centrifugal-section, a plurality of pairs of break-rolls in said roll-section, a scalping sieve having coarse and fine screens 90 for the first set of break-rolls, a second set of break-rolls to which said coarse screen delivers its tailings, a scalping sieve for said second set of break-rolls having coarse and fine screens, a centrifugal in said 95 centrifugal-section, a conveyer delivering to said centrifugal, means for guiding the throughs from both sieves to said conveyer, a pair of reduction rolls, means for guiding the tailings from the fine screen of said first 100 scalping sieve to said reduction-rolls, and means for guiding the tailings from the fine screen of said second scalping sieve to said reduction-rolls.

6. In a mill of the class described, the 105 combination of a casing having a roll-section and a centrifugal-section, a plurality of pairs of break-rolls in said roll-section, a scalping sieve having coarse and fine screens for the first set of break-rolls, a second set 110 of break-rolls to which said coarse screen delivers its tailings, a scalping sieve for said second set of break-rolls having coarse and fine screens, a centrifugal in said centrifugal-section, a conveyer delivering to said 115 centrifugal, means for guiding the throughs from both sieves to said conveyer, a pair of reduction-rolls, means for guiding the tailings from the fine screen of said first scalping sieve to said reduction-rolls, means for 120 guiding the tailings from the fine screen of said second scalping sieve to said reduction-rolls, a second pair of reduction-rolls, and means for delivering material from said first reduction-rolls to said second reduction-rolls. 125

7. In a mill of the class described, the combination of a casing having a roll-section and a centrifugal section, a plurality of pairs of break-rolls in said roll-section, a 130

- scalping sieve having coarse and fine screens for the first set of break-rolls, a second set of break-rolls to which said coarse screen delivers its tailings, a scalping sieve for said 5 second set of break-rolls having coarse and fine screens, a centrifugal in said centrifugal-section, a conveyer delivering to said centrifugal, means for guiding the throughs from both sieves to said conveyer, a pair of 10 reduction-rolls, means for guiding the tailings from the fine screen of said first scalping sieve to said reduction-rolls, means for guiding the tailings from the fine screen of said second scalping sieve to said reduction-rolls, means for guiding the tailings from said centrifugal to said reduction-rolls, a second pair of reduction-rolls, and means 15 for delivering material from said first reduction-rolls to said second reduction-rolls.
- 20 8. In a mill of the class described, the combination of a casing having a roll-section and a centrifugal-section, a plurality of pairs of break-rolls in said roll-section, a scalping sieve having coarse and fine 25 screens for the first set of break-rolls, a second set of break-rolls to which said coarse screen delivers its tailings, a scalping sieve for said second set of break-rolls having coarse and fine screens, a centrifugal in said 30 centrifugal-section, a conveyer delivering to said centrifugal, means for guiding the throughs from both sieves to said conveyer, a pair of reduction-rolls, means for guiding the tailings from the fine screen of said first 35 scalping sieve to said reduction-rolls, means for guiding the tailings from the fine screen of said second scalping sieve to said reduction-rolls, a second pair of reduction-rolls, means for delivering material from said 40 first reduction-rolls to said second reduction-rolls, means for guiding the tailings from the fine screen of said second scalping sieve to said first reduction-rolls, a second centrifugal in said centrifugal-section, and a conveyer delivering from said first reduction-rolls to said second centrifugal.
- 45 9. In a mill of the class described, the combination of a casing having a roll-section and a centrifugal section, a plurality of 50 pairs of break-rolls in said roll-section, a scalping sieve having coarse and fine screens for the first set of break-rolls, a second set of break-rolls to which said coarse screen delivers its tailings, a scalping sieve for 55 said second set of break-rolls having coarse and fine screens, a centrifugal in said centrifugal section, a conveyer delivering to said centrifugal, means for guiding the throughs from both sieves to said conveyer, 60 a pair of reduction-rolls, means for guiding the tailings from the fine screen of said first scalping sieve to said reduction-rolls, means for guiding the tailings from the fine screen of said second scalping sieve to 65 said reduction-rolls, a second pair of re-

duction rolls, means for delivering material from said first reduction-rolls to said second reduction-rolls, a second centrifugal in said centrifugal section, a conveyer delivering from said first reduction rolls to 70 said second centrifugal, a third centrifugal in said centrifugal section, and a conveyer delivering from said second reduction rolls to said third centrifugal.

75 10. In a mill of the class described, the combination of a pair of break-rolls, a second pair of break-rolls, a pair of reduction rolls, a scalping sieve for said first pair of break rolls having coarse and fine screens, means for guiding the tailings of the coarse 80 screen to said second pair of break-rolls, and means for guiding the tailings of said fine screen to said reduction rolls.

85 11. In a mill of the class described, the combination of a pair of break-rolls, a second pair of break-rolls, a pair of reduction rolls, a scalping sieve for said first pair of break-rolls having coarse and fine screens, means for guiding the tailings of the coarse 90 screen to said second pair of break-rolls, means for guiding the tailings of said fine screen to said reduction-rolls, a centrifugal, conveyer means delivering to said centrifugal, and means for guiding the throughs of said fine screen to said conveyer means.

95 12. In a mill of the class described, the combination of a pair of break-rolls, a second pair of break-rolls, a scalping sieve for said first pair of break-rolls having coarse and fine screens, means for guiding the tailings of said coarse screen to said second pair of break-rolls, a scalping sieve for said second pair of break rolls having coarse and fine screens, a centrifugal, conveyer means delivering to said centrifugal, means for guiding the throughs of said fine screens to said conveyer means, a bran-receiving reel, and conveyer means for delivering tailings from the coarse screen of the scalping sieve for said second set of break-rolls to said bran-receiving reel.

100 13. In a mill of the class described, the combination of a pair of break-rolls, a scalping sieve for said break-rolls having coarse and fine screens, a second pair of break-rolls 115 to which said coarse screen delivers, a second scalping sieve for said second break-rolls having coarse and fine screens, a bran-receiving reel, and conveyer means for delivering tailings from the coarse screen of 120 said second scalping sieve to said reel.

125 14. In a mill of the class described, the combination of a pair of break-rolls, a scalping sieve for said break-rolls having coarse and fine screens, a second pair of break-rolls 130 to which said coarse screen delivers, a second scalping sieve for said second pair of break-rolls having coarse and fine screens, a bran-receiving reel, conveyer means for delivering tailings from the coarse screen of said

second scalping sieve to said reel, reduction-rolls, and conveyer means for returning the overtails of said bran reel to said reduction-rolls.

- 5 15. In a mill of the class described, the combination of a pair of break-rolls, a second pair of break-rolls, a scalping sieve for said first pair of break-rolls having coarse and fine screens, means for guiding the tailings 10 of said coarse screen to said second pair of break-rolls, a scalping sieve for said second pair of break-rolls having coarse and fine screens, a centrifugal, conveyer means delivering to said centrifugal, means for guiding 15 the throughs of said fine screens to said conveyer means, a bran-receiving reel, conveyer means for delivering tailings from the coarse screen of the scalping sieve for said second pair of break-rolls to said bran-receiving reel, reduction-rolls, and conveyer means for returning overtails from both said 20 centrifugal and said bran-receiving reel to said reduction-rolls.

16. In a mill of the class described, the combination of a pair of break-rolls, a second 25 pair of break-rolls, a scalping sieve for said first pair of break-rolls having coarse and fine screens, means for guiding the tailings of said coarse screen to said second pair of break-rolls, a scalping sieve for said second 30 pair of break-rolls having coarse and fine screens, a centrifugal, conveyer means delivering to said centrifugal, means for guiding the throughs of said fine screens to said conveyer means, a pair of reduction-rolls, means for guiding the tailings of both of the fine sieves of said break-roll scalpers to said reduction rolls, a second 35 centrifugal conveyer means delivering to said second centrifugal, and means for guiding the tailings of the coarse screen of said scalper for the second pair of break-rolls to said last named conveying means. 40

In testimony whereof I have hereunto set my hand.

LUCIUS FREEMAN LITTLE.
